UNITED STATES PATENT OFFICE.

ADOLPH RANSON, OF SOUTH CHARLESTON, WEST VIRGINIA, ASSIGNOR OF ONE-HALF
TO STAUNTON ISAAC, OF SOUTH CHARLESTON, WEST VIRGINIA.

PARACHUTE.

1,244,129.

Specification of Letters Patent. Patented Oct. 23, 1917.

Application filed April 30, 1917. Serial No. 165,532.

To all whom it may concern:

Be it known that I, ADOLPH RANSON, a citizen of the United States, residing at South Charleston, in the county of Kanawha, State of West Virginia, have invented a new and useful Parachute; and I do hereby declare the following to be a full, clear, and exact description of the invention, such as will enable others skilled in the art 10 to which it appertains to make and use the same.

The present invention relates to a life saving parachute for the use of aviators, and has for its object to provide a device of this 15 character which embodies novel features of construction whereby an aviator may be assured of a safe descent to the ground in the event of a mishap or accident.

Further objects of the invention are to 20 provide a life saving parachute of this character which is comparatively simple and inexpensive in its construction, which can be worn by an aviator while making a flight without any inconvenience or discomfort, 25 which will automatically become distended and expanded into operative position in the event of the aviator being thrown from the machine, and which will cause the aviator to drop in an upright position with his head 30 and shoulders uppermost.

With these and other objects in view, the invention consists in certain novel combinations and arrangements of the parts as will more fully appear as the description 35 proceeds, the novel features thereof being pointed out in the appended claims.

For a full understanding of the invention, reference is to be had to the following description and accompanying drawings, in 40 which:—

Figure 1 is a front elevation of a parachute constructed in accordance with the invention, showing the same as fully expanded in operative position.

Fig. 2 is a vertical longitudinal sectional view through the same.

Fig. 3 is a side view of an aviator provided with the parachute, the latter being shown in a collapsed condition.

Fig. 4 is an enlarged side elevation of the shoulder harness.

Fig. 5 is a top plan view of the same.

Fig. 6 is an enlarged detail view of one of the leg bands.

Corresponding and like parts are referred to in the following description and indicated in all the views of the drawings by the same reference characters.

In attaching the parachute to the body of an aviator, a shoulder harness is employed. This shoulder harness is shown as including a band 1 which encircles the body of the aviator A at a point just below the arms, said band being provided with looped shoulder straps 2 which extend upwardly over the shoulders of the aviator. Suitable pads 3 may be provided, if desired, and the body encircling band 1 is split so that it can be contracted or expanded as may be necessary to fit the particular aviator. The ends 70 of the split band 1 at the back of the aviator are shown as formed with outstanding ears 4 which are connected by a pin 5, the end of the pin being threaded to receive a thumb nut 6 which can 75 be manipulated to adjust the size of the band as required. The reel 7 is journaled upon the pin 5 between the ears 4, and a coil spring 8 is arranged within the reel and operatively connected thereto for rotating the 80 latter to wind a cable 9 thereon, in a manner and for a purpose to be hereinafter described.

A lower and relatively small parachute 10 is applied to the body encircling band 1 so 85 as to hang therefrom and normally fold or collapse against the body of the aviator, as indicated by Fig. 3. The edge portions of the lower parachute 10 are connected by cords 11 to leg bands 12 which are applied to 90 the legs of the aviator, preferably at a point just below the knees as indicated more clearly by Fig. 1. These leg bands may be formed of any suitable material, and are shown as being adjustable by means of buckles 13. 95 Immediately to the rear of the shoulder engaging harness the lower fabric parachute 10 is formed with an opening which communicates with an upwardly extending fabric air tube or conduit 14. This air conduit 100 14 is collapsible so that it can be folded in a small amount of space when not in use, although when the lower parachute 10 is distended and in operative position it will be obvious that the rapid passage of air upwardly through the conduit 14 will maintain the same in a distended position, as indicated by Fig. 2. A ring 15 of aluminum

or other suitable material is slidably mounted upon the air conduit 14 so as to be movable up and down thereon. This ring 15 is connected by cords 16 to the periphery of 5 an upper and larger parachute 17 which is also formed of a suitable fabric so as to be collapsible, and which is intended to provide the main supporting means when the device is in use. A small central opening 10 17^a is preferably provided at the middle of the upper parachute 17, although this opening is not sufficiently large to interfere with the efficiency of the parachute. The sliding ring 15 is suitably connected by means of the 15 diverging branch cables 9^a to the upper end of the before mentioned cable 9 which is adapted to be normally wound upon the spring actuated reel 7. Preparatory to collapsing the parachute the sliding ring 15 is moved downwardly to the lower end of the 20 air conduit 14, the cable 9 being automatically wound upon the reel 7. The upper parachute 17 and air conduit 14 can then be folded together and compactly rolled into a 25 bundle B adapted to fit against the back, as indicated by Fig. 3. Everything remains loose, however, so that in the event of a sudden and unexpected fall from the airship the lower parachute 10 would expand and 30 cause a flow of air upwardly through the conduit 14 such as would expand the conduit and also cause the upper parachute 17 to be expanded. The ring 15 would rise gradually upon the conduit 14 until the cable 9 35 was completely unwound from the reel 7. The cable 9 would then act as a stop to hold the ring 15 in position.

A vane C is mounted upon the shoulder harness and constructed to swing automatically into operative position when the 40 aviator drops from his seat, and cause him to descend in an upright position with his head and shoulders uppermost. This vane includes side bars 18 which diverge from 45 each other and have their lower ends hinge- 50 dly connected at 20 to the top of the shoulder straps 2. The side bars 18 are connected by a thickness 21 of flexible fabric which is adapted to flex and yield as may be required 55 to conform to the shape of the body when swung downwardly, but which will offer a sufficient resistance to the air when the vane is projected vertically upward from the shoulders to insure that the aviator will descend in an upright position. Springs 22 60 are applied to the hinge connections 20 between the ends of the bars 18 and the shoulder straps 2, said springs normally tending to swing the vane upwardly into an upright 65 position, although the vane is foldable rearwardly against the action of the springs. Shoulders 23 limit the forward swinging movement of the vane, and coöperate with the springs 22 to hold the vane securely in 70 an upright position after it has been released 75 and permitted to swing upwardly. The side bars 18 of the vane are curved or deflected outwardly at a point toward the pivot ends thereof, as indicated at 19, thereby providing a clearance space for the reception of 70 the rolled bundle B when the upper parachute 17 and air conduit 14 are collapsed and the vane C swung rearwardly and downwardly into inoperative position. As indicated by Fig. 3, the side bars 19 then 75 extend downwardly along opposite sides of the body of the aviator, so that when the aviator is in flight he will be sitting upon the fabric portion 21 of the vane, thereby holding the vane downwardly against the 80 action of the springs 22. The upper parachute 17 and air conduit 14 will then be rolled to form the bundle B, while the lower parachute 10 will be collapsed in the manner of a skirt against the body of the aviator. 85 The parachute will not interfere in any manner with the freedom of movement of the aviator, although if he should be unexpectedly thrown from his seat the vane C will be immediately swung upwardly into 90 operative position by the springs 22, thereby causing him to return to an upright position even though he may have been initially thrown head foremost. The lower parachute 10 will then expand into operative position, whereupon the air pressure at the top 95 thereof will cause the bundle B to unroll and the air conduit 14 become distended. The passage of air through this air conduit will act upon the upper parachute 17 to dis- 100 tend the latter. This upper parachute 17, together with the ring 15 will rise slowly and unwind the cable 9 from the spring actuated reel 7 until the cable is completely 105 unwound from the reel and the ring reaches the upper limit of its movement. The parachute will then be completely distended and in operative position so that the aviator will descend slowly and be enabled to reach the earth in safety. It will be obvious that the 110 device can be worn without any discomfort and without interfering in any manner with the necessary freedom of movement of the aviator, and the construction is such that the 115 parachute will be automatically distended without any manipulation or preparation on the part of the aviator, thereby insuring a safe descent even though he may meet with an unexpected accident and be thrown from the machine without warning. When the 120 aviator is walking upon the ground, the vane C will be held in inoperative position by suitable straps 25. These straps, however, will be unfastened when he takes his position in an airship preparatory to making a flight, thereby leaving the vane C free to be swung upwardly into inoperative position should the aviator be thrown from his seat.

Having thus described the invention, what 130

I claim as new and desire to secure by Letters Patent, is:—

1. A device of the character described, including a body encircling band, a lower collapsible fabric parachute pendent from the body encircling band, a collapsible air conduit extending upwardly from the lower parachute, and an upper collapsible fabric parachute arranged above the air conduit so as to be acted upon by the air passing upwardly through the same. 5
2. A device of the character described, including a body encircling band, a lower collapsible fabric parachute pendent from the body encircling band, leg bands, cords connecting the leg bands to the lower parachute, an upper collapsible fabric parachute, an air conduit extending upwardly from the lower parachute, a ring surrounding the air conduit, and cords connecting the ring to the upper parachute. 15
3. A device of the character described, including a body encircling band, a lower collapsible fabric parachute pendent from the body encircling band, leg bands, cords connecting the leg bands to the lower parachute, an air conduit extending upwardly from the lower parachute, a ring slideable upon the air conduit, stop means for limiting the sliding movement of the ring, an upper parachute, and cords connecting the ring to the upper parachute. 25
4. A device of the character described, including a body encircling band, a lower collapsible fabric parachute pendent from the body encircling band, leg bands, cords connecting the leg bands to the lower parachute, an air conduit extending upwardly from the lower parachute, a ring slideable upon the air conduit, a stop cord for limiting the upward movement of the ring, a reel for holding the slack of the stop cord, an upper parachute, and cords connecting the ring to the upper parachute. 35
5. A device of the character described, including a body encircling band, a lower collapsible fabric parachute pendent from the body encircling band, leg bands, cords connecting the leg bands to the lower parachute, a collapsible fabric air conduit extending upwardly from the lower parachute, an upper collapsible fabric parachute adapted to be arranged above the air conduit when in operative position, a ring slideable upon the air conduit, stop means for limiting the upward sliding movement of the ring, and cords connecting the ring to the upper parachute. 50
6. A device of the character described, including a split body encircling band having outstanding ears at the ends thereof, a pin connecting the ears, a nut threaded upon the pin for co-operation therewith to adjust the effective size of the body encircling band, 65 a reel mounted upon the pin, a collapsible
- parachute, and a cable operatively connected to the collapsible parachute and adapted to be wound upon the reel. 70
7. A device of the character described, including a split body encircling band having outstanding ears at the ends thereof, a pin connecting the ears, a nut threaded upon the pin for co-operation therewith to adjust the effective size of the band, a reel mounted upon the pin, a lower collapsible parachute 75 pendent from the band, an air conduit extending upwardly from the lower parachute, an upper collapsible fabric parachute arranged above the air conduit to be acted upon by the air passing upwardly through 80 the same, a ring slideable upon the air conduit, cords connecting the ring to the upper parachute, and a stop cable connected to the ring and adapted to be wound upon the before mentioned reel. 85
8. A device of the character described, including shoulder harness, a vane hingedly connected to the shoulder harness and adapted to fold against the body, means for projecting the vane upwardly when released, 90 and a collapsible parachute member operatively connected to the shoulder harness and adapted to be held in a collapsed condition by the vane when the latter is swung into inoperative position. 95
9. A device of the character described, including a shoulder harness, a vane hingedly connected to the shoulder harness and adapted to fold against the body, means for projecting the vane upwardly when released, a lower collapsible parachute applied to the shoulder harness, a collapsible air conduit extending upwardly from the lower parachute, an upper collapsible fabric parachute adapted to be arranged above the air 100 conduit to be acted upon by the air passing upwardly through the same, the upper parachute and air conduit being adapted to be engaged in a collapsed condition by the vane when the latter is folded against the body. 105
10. A device of the character described, including shoulder harness, a vane including side bars hingedly secured to the shoulder harness and connected by fabric, the vane being adapted to be swung downwardly with the side bars on opposite sides of the body of the aviator, means for projecting the side bars upwardly when released, and a parachute operatively connected to the shoulder harness. 115
11. A device of the character described, including shoulder harness, a vane hingedly connected to the shoulder harness and adapted to be folded against the body, a portion of the vane being curved outwardly, means 125 for swinging the vane into an unright position when released, and a collapsible parachute operatively connected to the shoulder harness and adapted to be received within the outwardly curved portion of the vane 130

when it is in a collapsed condition and the vane is folded downwardly.

12. A device of the character described, including shoulder harness, a vane hingedly connected to the shoulder harness and adapted to be folded against the body, said vane being formed with an outwardly curved portion, means for swinging the vane upwardly when released, a lower collapsible parachute 5 pendent from the shoulder harness, a collapsible air conduit extending upwardly from the lower parachute, a ring surrounding the air conduit, and an upper collapsible parachute adapted to be arranged above the 10 air conduit to be acted upon by the air pass- 15

ing upwardly through the same, said upper parachute being connected to the ring and the upper parachute and air conduit being adapted to be collapsed and received within the outwardly curved portion of the vane 20 when the latter is swung downwardly against the body.

In testimony whereof I have signed my name to this specification in the presence of two subscribing witnesses.

ADOLPH RANSON.
